UNITED STATES PATENT OFFICE.

FELIX KOHN, OF VIENNA, AUSTRIA-HUNGARY.

DESIGN FOR A CHAIR-BACK.

SPECIFICATION forming part of Design No. 17,448, dated July 12, 1887.

Application filed May 14, 1887. Serial No. 238,276. Term of patent 7 years.

To all whom it may concern:

Be it known that I, FELIX KOHN, a citizen of Austria-Hungary, residing at Vienna, Austria-Hungary, have invented and produced a new and original Design for Chair-Backs, of which the following is a specification, reference being had to the accompanying photograph, forming part thereof, which is a perspective view of a chair embodying my design. The leading feature of my design consists in the outer bar of the chair-back A above the seat B, sloping gradually outward, then curving inward at a, forming in the center of the chair-back a slight hollow or depression, b, which rests upon the loop-shaped upright center portion, C, extending from the seat of the chair to the hollow or depression b, as shown.

legs, and braces of the chair are of the ordinary or suitable form.

This design gives to the chair-back a very pleasing and handsome appearance. 20

I claim—

The design for a chair-back herein shown and described, the same consisting of the outer bar, A, that forms the hollow or depression b, and of the loop-shaped upright center portion, C, extending from the seat of the chair to the hollow or depression b, as shown. 25

FELIX KOHN.
